UNITED STATES PATENT OFFICE

2,436,113

AIRPLANE PROPELLER

David W. Main, Denver, Colo.

Application October 5, 1942, Serial No. 460,759

8 Claims. (Cl. 244—9)

1

This invention relates to improvements in airplanes and has reference more particularly to an improvement in propeller mechanisms of the type described and claimed in my copending application Serial No. 457,623, filed September 7, 1942, now Patent No. 2,397,189, issued March 26, 1946.

One of the objects of this invention is to provide a simple and reliable mechanism for improving the maneuverability of airplanes and to produce greater lifting power at the take-off whereby the airplane can be launched from a shorter field and whereby it may take-off with a greater load on a given take-off run.

Another object is to produce an airplane of greater than ordinary stability.

A further object is to produce an airplane of great climbing power by means of which a given altitude can be reached in a very short time.

A still further object is to produce a mechanism that will serve to produce both a lifting and a tractive force and which shall also be provided with means for proportioning and varying the lifting and tractive forces during flight.

The above and other objects that may become apparent as the description proceeds and others to which attention may be directed are obtained by means of a construction and an arrangement of parts that will now be described in detail and for this purpose reference will be had to the accompanying drawing in which the invention has been illustrated, and in which:

Figure 1 is a perspective view showing my invention applied to an airplane;

Figure 2 is a front elevation showing the invention separated from the airplane;

Figure 3 is a section taken on lines 3—3, Figure 2;

Figure 4 is a section taken on lines 4—4, Figure 2;

Figure 5 is a front elevation of one of the vanes of a rotating member;

Figure 6 is a top plan view, shown in a more or less diagrammatic manner, of the mechanism shown in Figure 2;

Figure 7 is a view somewhat similar to that shown in Figure 2, but showing a slightly modified form of construction.

In the drawing reference numeral 10 designates the fuselage of an airplane which, in this particular case is provided with coaxial propellers 11 and with wings 12. Positioned underneath the wings are auxiliary propellers and lifting devices comprising two elongated rotors which have been designated by letters A and B. The construction of the auxiliary devices will now be

described and for this purpose reference will be had more particularly to Figures 2, 3, 4 and 5.

A shaft 13 is journaled in suitable bearings in the fuselage 10 and extends through another bearing in a downwardly extending bracket 14. Surrounding the shaft is a hollow cylindrical member 15 from opposite ends of which spokes 16 radiate. The outer ends of the spokes are forwardly curved as shown at 17 in Figures 3 and 4 and the extreme ends are connected by means of a bar 18. Positioned between the bar 18 and the outer circumference of the cylinder 15 are blades 19. These blades are of streamline cross section as shown quite clearly in Figures 3 and 4. The blades are pivotally connected with the spokes 16. One end pivot extends through the spoke and terminates in a crank arm 20. The outer ends of the crank arms are pivotally connected to a connecting rod 21 from which a pin 22 extends. The axes of the cranks are inclined at approximately 45 degrees to the planes of the blades so that when the latter moves through 90 degrees, in the manner to be hereinafter explained, the crank arms will never make an angle of less than 45 degrees with the spokes. Secured to or formed integral with the bearing through which shaft 13 extends is a circular disk 23 that is provided on the surface adjacent the rotating element with a cam groove which has been shown by broken lines in Figure 4. The cam groove consists of two circular arcs 24 and 25 connected by inclined grooves 26. The radius of the arc 24 is shorter than the radius of the arc 25 and these radii are so calculated that when the pin or pins 22 are in the circular arc 24 the blades will project substantially perpendicular to the axis of the spokes in such a way that when the member rotates the blades will cut the air in the manner of a knife blade. When the pin 22 reaches the inclined portion 26 of the groove, it will move outwardly until it enters the arcuate groove 25 and during this movement the blades 19 will close until they assume the position shown in the lower right-hand portion of Figure 4. When the pin 22 reaches the lowermost inclined section 26, the blades will again be moved into open position. The feathering of the blades that is effected by the cam mechanism just described results in a rotor in which the resistance of the air is reduced to a negligible quantity during the upward movement and increased to a maximum during the downward movement. It is evident that a rotor having blades that open and close in the manner illustrated in Figure 4 and rotating in the direc-

tion of the arrow will exert a lifting power that is opposed slightly, if at all, by the upward movement of the blades.

Rotor A extends substantially at right angles to the axes of the fuselage and the blades are positioned so as to extend helically in the nature of lefthand threads when the rotor positioned at the right of the fuselage in Figure 1 is considered. In order to make it practical to turn the blades, they must be straight between the pivots and in order to effect this they are constructed in a manner shown in Figure 5 in which a member 27 connects the inner ends of the spokes and has a curved edge that fits the outside of the cylinder 15.

Although a single rotor will exert a considerable effect, better results will be obtained if another rotor B is connected therewith in the manner shown in the drawing. The rotor B is upwardly and rearwardly inclined and its shaft 28 has its inner end pivoted in a bearing 29 that has been shown as being integrally connected with bracket 14. A cam plate 23a is secured to the bearing 29 and operates in the same manner as explained in connection with Figure 4. The upward and outward inclination of the blades produces a stream of air that flows upwardly and rearwardly, thereby stabilizing the airplane at the same time that it effects a tractive and lifting force.

It may be desirable to adjust the cam plates 23 and 23a rotarially during flight so as to vary the portion between the lifting and the tractive effort, and in Figures 2 and 7 means have been indicated for this purpose. Cam plates 23 and 23a are formed on their outer edges with sprocket teeth and a shaft 31 is journaled in bearings in the fuselage and also in the bracket 14. Secured to the shaft are two sprocket wheels 32 and 33 that are connected by means of sprocket chains 34 with the cam disks. A crank 35 has been indicated as means for rotating the shaft 31. When thus equipped the operator can vary the effect of the auxiliary means to better suit various operating conditions. The adjusting mechanism shown in Figures 2 and 7 is merely illustrative of means and such modifications may be made as become necessary to accomplish the result desired. For example, instead of the crank 35 connected directly with shaft 31, a worm gear drive may be substituted as this is nonreversible and self-locking.

Greater adaptability can be had if sections A and B are rotated independently so that their speed of rotation may be adjusted to obtain the best results and this can be effected by making the shaft 13 tubular and inserting therethrough the shaft 28' to which the universal 30 is connected.

Referring again to Figure 7, attention is called to the fact that in this modification the rotor B has been shown as rigidly connected to an inclined portion of shaft 28a, as in the construction shown in Figure 2, which rotates about an axis substantially coincident with that of shaft 13. This is effected by providing the shaft 28a with an outer crank arm 36 that terminates in a journal 37. With this construction the rotor B moves in such a way that shaft 28a generates the surface of a frustum of a cone. The rotary movement of the rotor B gives an effect that simulates the action of a bird's wing during flight and greatly increases the effectiveness of this mechanism.

The rapid opening and closing of the blades 75 tained.

19 has a tendency to produce severe strains in stopping and starting and although not shown on the drawing, some resilient cushioning means is contemplated for the purpose of cushioning the blades on closing and producing a resilient force tending to move them to open position.

In the present embodiment the wings 12 have been shown of ordinary construction, but under certain circumstances the wings may be more or less skeletonized so as to have the airplane depend more directly for its supporting force on the operation of the rotating members.

By means of the cam disk 23, the particular periods in the rotation when the blades open and close can be varied and it is therefore possible to so adjust the parts that section A effects primarily a tractive effort, while section B is directed more particularly to producing a lifting force or this arrangement may be reversed, if desired. Instead of a single means for simultaneously adjusting both cam disks a separate means may be provided for each so that the two rotors may be adjusted differently in accordance with the exigencies of the situation. By means of the adjustment of the blades, it is possible to produce such large lifting forces that the plane may travel very slowly over an object, thereby making it possible to more accurately discharge bombs or other projectiles.

In the embodiment illustrated, the actual rotors are provided under each wing only, but it is possible and sometimes preferable to also provide the stabilizing wings at the rear of the fuselage with similar devices in which case the airplane will have added lifting power and increased stability.

Although the propelling devices have been shown as applied to an airplane having the usual form of tractor propeller and have been referred to as "auxiliary" propellers, it is to be understood that by suitably modifying the plane construction, the usual propeller may be omitted.

On the drawing and in the above description, sections A and B have been shown and described as rotating at the same speed which is quite usual and which may be accomplished by connecting the two shafts 13 and 28 by the universal 30.

In the above description and on the drawings two sections A and B have been described and shown. In some instances it may be desirable to employ a single section, like A, and so construct the same that the tractive effort and the lifting effort can be independently modified by suitable means, as, for example, means for changing the effect of the radial depth of the vanes or their pitch or their angle of attack.

Referring to Figure 4, reference numeral 26, it will be noted that under the arrangement shown the blades are reversible at this point in order to continuously present their leading edge in the direction of rotation for more effective performance. It has been found that reversal or flipping of the blades in this area adds a function of additional propulsion. As actually constructed, the mounting of pivot point of the blades is closer to the leading edge than to the following edge and therefore the blades tend to turn in the desired direction due to natural forces and especially where the channel is widened between the areas 26 and 24 left hand side. The blades may then be allowed to hunt their own best position with least amount of drag through a section where normally only negative results are ob-

Having described the invention, what is claimed as new is:

1. In an airplane having a fuselage, and at least one pair of wings, propelling and lifting means associated with the airplane comprising, elongated propeller elements extending laterally from opposite sides of the fuselage, each propeller element comprising two sections, the sections nearest the fuselage being mounted for rotation about axes substantially perpendicular to the axis of the fuselage, means for rotating the elements in such a direction that their front surfaces move downwardly, the outer sections being mounted for rotation about upwardly and rearwardly extending axes, means for transmitting motion to the inner section, means for transmitting motion to the outer sections comprising a universal joint, each section having a plurality of radial longitudinal spaced spokes, blades positioned between the spokes and mounted for rotation about their axes from open to closed position, and means comprising a cam mechanism associated with each section for alternately opening and closing the blades as the section rotates.

2. In an airplane having a fuselage, and at least one pair of wings, propelling and lifting means associated with the airplane comprising elongated propeller elements extending laterally from opposite sides of the fuselage, each propeller element comprising two sections, the sections nearest the fuselage being mounted for rotation about axes substantially perpendicular to the axis of the fuselage, means for rotating the elements in such a direction that their front surfaces move downwardly, the outer sections being mounted for rotation about upwardly and rearwardly extending axes, means for transmitting motion to the inner sections, means for transmitting motion to the outer sections comprising a universal joint, each section having a plurality of radial longitudinally spaced spokes, blades positioned between the spokes and mounted for rotation about their axes from open to closed position, and means comprising a cam mechanism asso-

ciated with each section for alternately opening and closing the blades as the section rotates, and means for adjusting the positions of the cams during operation.

- 5 3. A device in accordance with claim 1 in which the blades extend helically about the sections of the propeller elements.
- 4. A device in accordance with claim 2 in which the blades extend helically about the sections of
- 10 10 the propeller elements.
- 5. A device in accordance with claim 1 in which means is provided for rotatably adjusting the cams.
- 6. A device in accordance with claim 2 in which means is provided for rotatably adjusting the
- 15 cams.
- 7. A device in accordance with claim 1 in which the two propeller sections are mounted for independent rotation.
- 20 20 8. A device in accordance with claim 2 in which the two propeller sections are mounted for independent rotation.
